DISCHARGE DEVICE, BASE, AND METHOD

William Makenny, Mountain View, N. J., assignor
to Westinghouse Electric Corporation, East
Pittsburgh, Pa., a corporation of Pennsylvania

Application May 8, 1945, Serial No. 592,696

9 Claims. (Cl. 176—32)

1

This invention relates to discharge devices, and more particularly to those having elongated envelopes with a base at each end.

The principal object of my invention, generally considered, is to provide an improved form of base for the ends of elongated discharge devices.

Another object of my invention is to provide a single-contact base for the end of a tubular discharge device, said base comprising a shell of insulating material such as a phenolic condensation product, of which "Bakelite" is typical, having a relatively large, generally-cylindrical flange for receiving the end portion of the envelope of said device, and a lug or extension with a tapered hole for guiding a lead from said device to a contact ferrule at the end of said lug.

A further object of my invention is to provide a base for a discharge device comprising an insulating shell having a lug, and an end contact member associated with said lug, and applied as by snapping over a bead on the end thereof or embedded in said end portion as a lining for a lead-receiving aperture.

A still further object of my invention is to provide a base for a discharge device, said base being formed of "Bakelite" or the like, with a metal contact ferrule at the end thereof, said "Bakelite" being stabilized in dimensions by "after baking" so as to insure that the ferrule will stay securely affixed.

Other objects and advantages of the invention will become apparent as the description proceeds.

Referring to the drawing:

Fig. 1 is a fragmentary elevational view of a discharge lamp embodying my invention.

Fig. 2 is an enlarged fragmentary elevational view of the end portion of the envelope of such a lamp with which a base, embodying my invention, is associated.

Fig. 3 is a fragmentary view, corresponding with Fig. 2, but further enlarged and showing a metal ferrule as it is being applied to the base lug.

Fig. 4 is a fragmentary sectional view of apparatus for molding the insulating or "Bakelite" portion of a base embodying my invention.

Fig. 5 is a view corresponding to Fig. 4, but showing a modification.

Fig. 6 is a fragmentary view, partly in elevation and partly in axial section, of a base such as shown in Fig. 2, but modified.

Referring to the drawing in detail, like parts being designated by like reference characters, and first considering the embodiment of my invention illustrated in Figs. 1 to 4, inclusive, there is shown a discharge device or lamp 11 compris-

2

ing an elongated envelope 12, having a flare tube 13 at each end from a press 14 of which project leads 15 and 16 carrying an electrode device 17.

The lamp of the present embodiment is one in which a functionally single lead member, which however may be in the form of a plurality of wires or strands in parallel, extends to each electrode, the discharge being initiated by voltage rather than by thermionic emission. For that reason, the lead wires 15 and 16 come together to a single contact, preferably brass, ferrule 18 on the base 19. The base shell 20 is here formed of insulating material, preferably "Bakelite", and has a generally cylindrical flange 21 which receives the reduced portion 22 at the connected end of the envelope 12, and with which it is connected by cement 23. The base shell 20 has a lug 24 projecting axially therefrom in a direction opposite to that of the flange 21, that is, from the transverse wall portion 25, which with the flange 21 forms the bottom of a cup-shaped element.

The lug 24 has an aperture or hole 26 extending axially and passing from the inner surface of the wall 25 to the tip of the lug 24. The aperture is desirably conical or tapering, that is, decreasing from the inner surface of the wall 25 to a relatively small aperture at the tip of the lug 26, as particularly illustrated in Fig. 2. This allows for convenient threading of the lead wires 15 and 16 into the aperture 26, and said leads are guided by funnel-shaped inner portion 27 into the more acutely tapering outer portion 28 of the aperture, that is, that portion beyond the outer plane of the transverse base wall 25. The outer portions of the leads 15 and 16 extend into the central aperture 29 of the ferrule 18, and are secured thereto in any desired manner, as by brazing or soldering 31.

In order to hold the metal ferrule 18 in place on the lug 24, said lug is desirably formed with a groove 32 defining a knob 33 therebeyond, and the ferrule 18 is formed with a bead 34, as by forcing the metal inwardly around the periphery, as illustrated in Figs. 2 and 3, the inner diameter of said bead being appropriate, as compared with the outer diameter of the knob 33, after fully curing or "after-baking" to stabilize the dimensions thereof, so that when the ferrule is forced over the knob, from the position of Fig. 3 to that of Fig. 2, the bead stretches sufficiently so that it slips over the knob and snaps into place in the flared groove 32, as illustrated in Fig. 2, the peripheral edge portion 35 of the ferrule at the same time being pressed over lug portion 36, inward-

ly of the groove 32, and finally seating in the relief groove 37 around the trunk of the lug 24.

In the embodiment illustrated in Figs. 2 and 3 the following dimensions and tolerances have been employed and found satisfactory for effecting the desired locking between the ferrule and the knob, but are not to be considered as limiting:

	Inches
Outer diameter of the knob	.258 to .260
Inner diameter of the bead	.245 to .250
Inner diameter at the groove in lug	.245 to .247
Diameter of lug at base	.296 to .298
Normal inner diameter of ferrule adjacent rim	.292 to .294

It will, therefore, be seen that the stretching of the bead over the knob may amount to from .008 to .015 inch and the stretching of the periphery of the ferrule over the base portion of the lug may amount to from .002 to .006 inch. All of these dimensions are on the assumption that the "Bakelite" shell is either fully cured in the mold or "after-baked," so as to cure to set it sufficiently that no appreciable contraction occurs after assembly with the ferrule.

In Fig. 4 are illustrated parts of apparatus for molding the "Bakelite" shell. This apparatus comprises a lower mold portion 38, an upper mold portion or plunger 39, and an aperture-forming inset 41. For removing the formed shell a knock-out pin 42 is provided, which during the molding operation forms the extreme bottom portion of the mold.

From a consideration of this mold it will be seen that the bottom portion 38 is formed as a single piece, not counting the knock-out pin 42, the uncured selected plastic or "Bakelite" being placed therein and squeezed by the plunger parts 39 and 41 to entirely fill the space between them and the mold bottom, as illustrated. After partial curing in the mold by suitable heating, the upper portions 31 and 41 rise, followed by upward movement of the knock-out pin 42 to remove the formed shell 19 from the mold, the material of said shell being sufficiently resilient at that time, so that the knob portion 33 is squeezed to pass through the bead portion 43 of the lower mold section 38, and then springs back to approximately the original size. After removal from the mold, the shells 19 are fully cured by "after-baking," the following time-temperature relationship; that is, holding at a curing temperature of 175° C. for 15 hours, having been found suitable for "Bakelite."

Instead of making the shell of the base, and then press-fitting the metal contact portion thereto, said contact portion or ferrule may be incorporated with the shell during the process of molding. Such an embodiment is illustrated in Fig. 5 in which the ferrule 18^a is placed in the lower mold element 38^a, generally like the portion 38 of the embodiment illustrated in Fig. 4. The uncured selected plastic or "Bakelite" is placed in said ferrule and portions of the mold not occupied thereby, and squeezed by the plunger parts 39^a and 41^a to entirely fill the space between them and the mold bottom and supported ferrule 18^a.

It will be seen that while the ferrule 18^a is desirably like that of the preceding embodiment and provided with a bead 34^a, the lower mold portion 38^a is unprovided with an interfitting boss portion, so that after the plastic has been pressed in the mold and ferrule, and sufficiently cured, the formed base may be removed by raising the mold upper portions 39^a and 41^a, followed by upward movement of the knock-out pin 42^a. In

the case of this embodiment, the "Bakelite" or other plastic is desirably cured in the mold, so that there is no shrinkage thereafter with respect to the ferrule, although it may if desired, be removed to another container for finishing the curing operation, as in the first embodiment.

Referring now to the embodiment of my invention illustrated in Fig. 6, there is shown a shell 19^b, which may be formed like the shell 19 of the first embodiment, except that a metal, preferably brass, ferrule 18^b shaped with an outstanding inner flange 44, as well as the outer flange 45 on the body portion 46, is placed in the bottom of a mold, such as illustrated in Fig. 4, prior to introduction of the "Bakelite" or other moldable material. When the plunger descends, the ferrule 18^b is molded in place in the plastic material, as illustrated, thereby avoiding the necessity of press fitting an exterior ferrule, as in accordance with the first embodiment.

As a further embodiment a ferrule, such as designated by the reference character 18^b in the preceding embodiment, may be formed without an inner flange, such as that there designated 44, and pressed in place in the formed shell, after the latter has been sufficiently cured, rather than being embedded in the plastic material to form it while in the bottom of the lower mold element.

From the foregoing, it will be seen that I have devised an improved form of base for discharge devices, such as fluorescent and other lamps. It will be understood that although the diameter of the flange on the base which is secured to the adjacent end of the lamp envelope may be changed to agree with a change in the diameter of the envelope, the lug portion and associated ferrule may be constant for all discharge devices of this general type, thereby adapting such lamps for use with sockets of uniform character.

Although preferred embodiments of my invention have been disclosed, it will be understood that modifications may be made within the spirit and scope of the appended claims.

I claim:

1. A discharge device comprising an elongated envelope and a base, said base comprising a shell of moldable insulating material with a generally cylindrical flange receiving and secured to an end portion of said envelope and a lug extending axially therefrom in a direction opposite to that of said flange, said lug having a hole receiving a lead from said device and formed with an exterior groove, and a metal contact ferrule formed with an interior bead, of appropriate diameter compared to the grooved lug, and secured to said lug by a pressed fit causing said bead to snap into the lug groove, said lead connecting with said ferrule.

2. A discharge device comprising an elongated envelope and a base, said base comprising a "Bakelite" shell with a generally cylindrical flange receiving and secured to an end portion of said envelope and a lug extending axially therefrom in a direction opposite to that of said flange, said lug having a hole and formed with an exterior groove defining an end knob with a diameter of about .259", a lead from said device disposed in said hole, a metal contact ferrule formed with an interior bead with an interior diameter of about .247", and secured to said lug by a pressed fit causing said bead to snap over said knob and into the lug groove, and means connecting said lead with said ferrule.

3. A base for a discharge device comprising a shell of moldable insulating material with a gen-

erally cylindrical flange to receive and be secured to an end portion of the envelope of said device, a lug extending axially therefrom in a direction opposite to that of said flange, said lug having a hole for receiving a lead from said device and formed with an exterior groove, and a metal contact ferrule formed with an interior bead, of appropriate diameter compared with the grooved lug, and secured to said lug by a press fit, causing said bead to snap into the lug groove, so that said ferrule provides a contact for connection with said lead.

4. A base for a discharge device comprising a "Bakelite" shell with a generally cylindrical flange adapted to receive and be secured to an end portion of the envelope of said device, a lug extending axially therefrom in a direction opposite to that of said flange, said lug having a hole for receiving a lead from said device and formed with an exterior groove defining an end knob having a diameter of about .259 inch, and a metal contact ferrule formed with an interior bead having an interior diameter of about .247 inch and secured to said lug by a press fit, causing said bead to snap over said knob and into said lug groove and be thus held in place for connection with said lead.

5. A base for a discharge device comprising a stabilized "Bakelite" shell with a generally cylindrical flange adapted to receive and be secured to an end portion of the envelope of said device, a lug extending axially therefrom in a direction opposite to that of said flange, said lug having a hole for receiving a lead from said device and formed with a trunk having a diameter of about .297 inch and an exterior groove defining an end knob having a diameter of about .259 inch, and a metal contact ferrule formed with a rim having a normal inner diameter of .293 inch, and an interior bead having an interior diameter of about .247 inch and secured to said lug by a press fit, causing said rim to be pressed over said trunk and said bead to snap over said knob into said lug groove and be thus held in place for connection with said lead.

6. A base for a discharge device comprising an insulating shell with a generally cylindrical flange adapted to receive and be secured to an end portion of the envelope of said device and a lug extending axially therefrom in a direction opposite to that of said flange, said lug having an axial hole for receiving a lead, the outer portion of said lug having a metal ferrule lining said hole for connection with said lead.

7. A base for a discharge device comprising a shell of moldable insulating material with a generally cylindrical flange adapted to receive and be secured to an end portion of the envelope of said device, a lug extending axially therefrom in a direction opposite to that of said flange, said lug having a central aperture flaring from its end in the same direction as said flange, for receiving a lead from said device, formed with a trunk having a diameter of about .297 inch and an exterior groove defining an end knob having a diameter of about .259 inch, and a metal contact ferrule formed with a rim having a normal inner diameter of .293 inch, and an interior bead having an interior diameter of about .247 inch

and secured to said lug by a press fit, causing said rim to be pressed over said trunk and said bead to snap over said knob into said lug groove and be thus held in place for connection with said lead, the peripheral edge of said ferrule being flared outwardly to facilitate starting the fitting on said lug, and said shell having a correspondingly formed relief groove around the trunk of the lug, snugly receiving said flared edge portion when the ferrule is in place.

8. A discharge device comprising an elongated envelope and a base, said base comprising a shell of moldable insulating material with a generally cylindrical flange receiving and secured to an end portion of said envelope, a lug extending axially therefrom in a direction opposite to that of said flange, said lug having a central aperture flaring from its end toward said envelope, formed with a trunk having a diameter of about .297 inch and an exterior groove defining an end knob having a diameter of about .259 inch, a lead from said device loosely disposed in said aperture, a metal contact ferrule formed with a rim having a normal inner diameter of .293 inch, and an interior bead having an interior diameter of about .247 inch and secured to said lug by a press fit, causing said rim to be pressed over said trunk and said bead to snap over said knob into said lug groove and be thus held in place for connection with said lead, the peripheral edge of said ferrule being flared outwardly to facilitate starting the fitting on said lug, and said shell having a correspondingly formed relief groove around the trunk of the lug, snugly receiving said flared edge portion when the ferrule is in place, and means connecting said lead with said ferrule.

9. A discharge device comprising an elongated envelope and a base, said base comprising an insulating shell with a generally cylindrical flange receiving and secured to an end portion of said envelope and a lug extending axially therefrom in a direction opposite to that of said flange, said lug having an axial hole flaring from its end toward said envelope, a lead from said device loosely disposed in said hole, a metal contact ferrule lining the outer edge portion of said lug, and means connecting said lead with said ferrule.
